UNITED STATES PATENT OFFICE.

WILLIAM H. RAMAGE, OF YOUNGSTOWN, OHIO.

APPARATUS FOR REMOVING ROLLS FROM FRAMES OF ROLLER-MILLS.

1,115,106.

Specification of Letters Patent. Patented Oct. 27, 1914.

Application filed January 3, 1914. Serial No. 810,261.

To all whom it may concern:

Be it known that I, WILLIAM H. RAMAGE, a citizen of the United States, residing at Youngstown, in the county of Mahoning and State of Ohio, have invented certain new and useful Improvements in Apparatus for Removing Rolls from Frames of Roller-Mills; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in apparatus for removing rolls from the frames of roller mills and comprises a simple and efficient apparatus of this nature whereby the rolls, which sometimes are of enormous weight, may be easily and quickly picked up from their bearings and removed and other rolls carried to and deposited within the bearings of the machine by suitable power driven apparatus.

The present invention comprises an apparatus of this nature having various details of construction and combinations and arrangements of parts which will be herein-after fully described, shown in the accompanying drawings and then specifically defined in the appended claims.

My invention is illustrated in the accompanying drawings, in which:—

Figure 1 is a side elevation of a part of a rolling mill showing the apparatus for lifting the roll in engagement with one end of the spindle of the roll. Fig. 2 is an end view in elevation of the frame showing the opening through which the rollers are moved to and from their bearings. Fig. 3 is a cross sectional view on line 3—3 of Fig. 1. Fig. 4 is a sectional view on line 4—4 of Fig. 1, and Fig. 5 is a section on line 5—5 of Fig. 1.

Reference now being had to the details of the drawings by letter, A, A designate the opposite sides of the frame of a roll mill, each having openings B formed therein of greater width than the diameters of the rolls C, each of which has a neck D, usually about half the diameter of the roll proper. Said necks are adapted to be mounted in "chocks" fitted into the housings or frame and sustain the weight of the roll and the opposite end of each roll is provided with a "wobbler"

having prongs or corners, usually four in number and by which the roll is driven, the said roll, necks and wobblers being one casting or forging. Said housings are shown as having a platform A' at their upper ends provided for supporting a motor which is adapted to operate means for adjusting rolls but which motor and adjusting means are not illustrated as they form no part of the present invention.

A suitable carrier or derrick, designated by letter H, is provided at its lower end with a socket portion H', conforming to and adapted to receive one end of the roll, and K designates a derrick carrying member having a clevis L engaged by a hook N, which latter is adapted to be connected to any suitable means for shifting from one point to another on a transmission mechanism the derrick with the roll engaged thereby. A counterbalance weight O is mounted on the horizontally disposed portion of the derrick or carrier H and an adjusting screw Q is mounted in threaded apertures in the counterbalance weight C and said member K. A grooved pulley S is fixed to one end of the screw Q and over which pulley a guard S' extends and a chain T passes about the grooved pulley and affords means for rotating the same and the screw for the purpose of adjusting the counterbalance weight to balance the vertical leg of the carrier or derrick. A suitable stirrup, designated by letter J, is fastened to the side of the vertical leg or derrick and is provided for the insertion of an ordinary lever or bar whereby an operator may steady the carrier when the lower end of the carrier is moved into engagement with the roll to be moved.

In operation, when it is desired to change a roll by removing the same from the frame, the "chocks" are first loosened, the carrier is brought adjacent to the roll mill at the socket end and the lower part of the carrier is moved into engagement with the end of the roll. The crane hook is then raised slightly, thus elevating the carrier and the roll with it. In the event of the roll not remaining horizontal, the operating wheel S may be turned in one direction or the other, thereby causing the member K to be moved and with it the counterbalance weight to cause the carrier and load to balance. This may be done rapidly as the rolls ordinarily in a mill would require only a maxi-

- 5   mum movement of the member K a few inches in order to balance the carrier and its load. The carrier may then be bodily moved with its load in order to remove the roll through the opening in the end of the frame and may be taken to any place desired and deposited and a new roll replaced by reverse movement of the operation described.
- 10   When the member K is adjusted to bring the latter directly over the center of gravity of the roll held by the socket at the lower end of the carrier, the horizontal leg of the carrier and likewise the axis of the roll 15   will then be truly horizontal for the upward pull by the carrier hook and the downward pull due to the weight of the roll will be coinciding vertical planes and hence the forces will be in equilibrium and avoiding 20   any tendency to rotation. At the same time, the weight of the vertical leg of the carrier will be exactly counterbalanced by the weight upon the horizontal end thereof.
- 25   What I claim to be new is:—
1. An apparatus for removing rolls from rolling mills comprising a carrier adapted to engage the neck at one end of a roll, an adjustable member in which a laterally extending portion of said carrier is adapted to 30   be adjustably held, a counterbalance weight upon the carrier and having a threaded aperture therein, and a screw engaging the threaded aperture in said counterbalance

weight and in said carrier supporting member, as set forth.

2. An apparatus for removing rolls from rolling mills comprising a carrier adapted to engage the neck at one end of a roll, an adjustable member in which a laterally extending portion of said carrier is adapted to 40   be adjustably held, a counterbalance weight upon the carrier and having a threaded aperture therein, a screw engaging the threaded aperture in said counterbalance weight and in said carrier supporting 45   member, a pulley fixed to said screw, and a chain passing about the pulley, as set forth.

3. An apparatus for removing rolls from rolling mills comprising a carrier having at its lower end a socket portion adapted to 50   receive the end of the neck of a roll, a supporting member mounted on a horizontally disposed portion of the carrier, a counterbalance weight upon the carrier, said counterbalance weight and supporting member having 55   registering threaded apertures, a screw engaging said apertures, a pulley fixed to the screw, and an endless chain passing about said pulley, as set forth.

In testimony whereof I hereunto affix my 60   signature in presence of two witnesses.

WILLIAM H. RAMAGE.
